UNITED STATES PATENT OFFICE.

HENRY H. CURTISS, OF NEW YORK, N. Y.

METHOD AND APPARATUS FOR PHOTOGRAPHING.

1,097,120.

Specification of Letters Patent.

Patented May 19, 1914.

Application filed June 21, 1911. Serial No. 634,585.

To all whom it may concern:

Be it known that I, HENRY H. CURTISS, a citizen of the United States of America, residing in the city of New York and State of New York, have invented an Improved Method and Apparatus for Photographing, of which the following is a specification.

The principal object of my invention is to photograph objects by as simple a method and apparatus as possible, and specially to photograph the appearance of surfaces, such as writing, printing, designs and pictures.

My invention consists in the method and apparatus herein described and set forth in the claims.

The accompanying drawing illustrates an embodiment of my apparatus by which my improved method may be carried out, in which—

20 Figure 1 is a transverse section on the line A—A of Fig. 3, Fig. 2 an end view, Fig. 3 a longitudinal central section on the line B—B of Fig. 1, but with one of the reels removed, and Fig. 4 a detail.

25 Similar characters represent like parts in all the figures.

1 is an oblong casing or box preferably of light sheet metal, such as aluminum. This casing is entirely closed except for 30 a narrow slot or opening 2 at its bottom extending longitudinally from end to end of the casing.

3 is a lamp supported within the casing 1, above the opening 2, and preferably extending about the length of said opening. Said lamp may be an incandescent electric lamp, such as shown in the drawings, or any other lamp producing a bright light.

4 is a reflector in the form of a casing, surrounding the top and sides of the lamp 3, and having its sides at the bottom contracted and terminating near the edges of the opening 2, but leaving a narrow longitudinal space or slit 5 between said edges 45 and sides through which a strip of sensitized paper or film may pass without friction, but so as to practically prevent the admission of light to the interior of the casing 1 from the outside. The ends 6 of the reflector casing 4 slope upwardly and inwardly so as to assist the top and sides of the reflector 4 in deflecting the light from the lamp through the opening 2. The inner surfaces of the reflector 4—6 should be of highly light re-

flecting quality, and said reflector may be 55 made of tin or similar sheet metal.

7 is an oblong plate of clear transparent glass or similar material closing the open bottom of the reflector 4. I have shown in the drawings this plate 7 with a downwardly 60 extending flange or tenon 7^a to either side of which the bottom of the reflector edges are turned, so as to hold said plate in place.

8 is a strip of transparent or translucent sensitized material on which the photograph 65 is to be taken. This strip is wound upon a reel 9 journaled inside the casing 1.

10 is a reel wound with a strip of opaque paper or similar material 11, said reel being journaled in the casing 1 in a similar manner to the reel 9. 12 is a take-up reel also journaled in the casing 1 and which is adapted to wind up the strip 8 after the exposure of the same and also to wind with it the opaque strip 11 from the reel 10 to prevent 75 undue exposure to the sensitized strip after the photograph has been taken on it. The reel 12 is caused to automatically wind up the strips 8 and 11 by the uncoiling of a previously coiled spring, as will hereinafter 80 be described.

13 are two sets of guide plates arranged on either side of the reflector 4 and between it and the bottom of the casing 1, and preferably so as to cover the strip 8 from the 85 opening 2 to some distance above said opening. These guides should also be curved and arranged as to have no edges or corners against which the strip 8 could rub. They may also, in order to protect the strip 90 8 from the light, be provided with black or light absorbing surfaces.

The delivery reel 9 bearing the non-exposed sensitized strip is separated from the take-up reel 12 by a longitudinal partition 95 14 dividing the casing 1 into two compartments. The surfaces of this partition 14 are preferably coated black or are light absorbing. The strip 8 should be fed down between the nearest set of guide plates 13, 100 through the nearest slit 5, under the glass plate 7, up through the next slit 5, and between the second set of guide plates 13 to the take-up roller 12, to which the opaque strip 11 should also be fed. The long opposite sides of the slot or opening 2 at the bottom of the casing 1 are formed of the lower edges of two oppositely sloping sides 15.

This construction provides not only that the plate 7 or what is under it may be the only contact surface of the apparatus with the surface to be photographed, but that all 5 the rest of the surface to be photographed that is not covered by the plate 7, can be seen.

The take up reel has a round socket 16 at the center of one end, and a post 17 angular in cross-section extending from the 10 center of the other end. A round pin 18 passes loosely through one end 19 of the casting 1 and is supported in bearings 20 on the outside of said casing. This pin 18 is provided with a transverse projection or 15 pin 21 and a coil spring 22 surrounding the pin 18 and bearing upon the cross pin 21 tends to bear said rod inward. A ring or other handle 23 attached to the outer end of the rod serves to draw the same outward 20 (against the action of the spring) and away from the reel 12.

The winding up mechanism of the reel 12 is the following: 24 is a coil spring casing provided with a central circular hub 25 journaled in a corresponding hole in the end 26 of the casing 1 (opposite to the end 19). This hub 25 is provided with an angular socket within which the post 17 may enter and be held. The spring casing 24 is provided with a circular flange 27 having arranged at intervals thereon, recesses 28, with which engages a spring dog or clutch 29. 30 is a post loosely journaled in a circular socket 30^a in the casing 24, and in 35 a fixed bearing 31 in front of said casing. 32 is a coil spring surrounding the post 30 within the casing 24, and which is secured at the inner end to said post, and at the outer end to the surrounding wall of the casing.

40 Secured to the post 30 is a toothed or ratchet wheel 33, and 34 is a pawl or dog loosely pivoted to the bearing 31 and engaging with the teeth of said wheel. 35 is a handle secured to the outer end of the post 30, by 45 which the same may be turned to wind up the spring, said winding causing the teeth of the wheel 33 to ride over the pawl 34, but the pawl (unless raised) preventing the unwinding of the spring from its center.

50 When the dog 29 is in engagement with one of the recesses 28, the spring 32 is prevented from unwinding from the outside, but if said dog be withdrawn from such engagement, the spring will unwind from the outside, and cause the casing 24 to revolve, as also the reel 12 if its post 17 is within the socket of the hub 25. 36 is the handle by which the apparatus is manipulated for photographing. This handle is hollow, as is 55 shown in Fig. 3, and is secured to the top of the casing 1. 37 is a vertically movable rod extending longitudinally within said handle through guide ways 38, and 39. The lower end of rod 37 loosely engages with

one arm of a lever 40, the other arm of said lever being connected with an upward extension of the dog 29 by a wire or other flexible connection 41. This connection is inclosed within a tubular casing 42 for the protection of the same. 43 is an electrical terminal secured to the upper surface of the support of guide 39, and 44 is the opposite electric terminal above 43, and on the under surface of a block 45 secured to the rod 37. A coil spring 46 between the guide 38 and 75 a knob 47, tends to normally keep the rod 37 raised, and the terminal 44 away from terminal 43. 3 is an incandescent lamp, the outer surface of which is preferably cylindrical, as shown at 48. The lamp extends 80 through the sloping ends 6 of the reflector 4, and is supported in tubular sockets 49 extending inward from the ends of the casing 1. The two line wires 50 and 51 from any 85 source of electric supply are connected respectively with one of the lamp terminals, and with the movable terminal 44, which is operated by the rod 37, and the connecting line 52 to complete the circuit when the two terminals are in contact, connects the other 90 terminal of the lamp 3 with the fixed contact 43 in the handle 36.

Wherever it is possible the surfaces inside the casing 1, and the outside surfaces of the reflector 4, should be black or light absorbing. I have shown the electric lines in the figures diagrammatically, but in practical use 95 they should be inclosed within the handle 36 and casing 1, and they and the terminals should be properly insulated from other 100 parts and devices. The reels 9 and 10 may be removably journaled in the casing 1 in any well known manner.

If it be desired to photograph a picture, design, or printed page, as for example on 105 the surface of a sheet 53 (see Fig. 1) the spring 32 should be first wound up as above described, the sensitized strip 8 should be fed between one set of guides 13, under and across the glass 7, up between the other 110 guides 13 to the reel 12, and the opaque strip 11 from the reel 10 should be fed to the reel 12. The apparatus should next be placed with the part of strip 8 that is under the glass 7 resting at the beginning 54 of 115 the printing or design or printing at the top of the page, with the glass 7 extending along and over the upper end of the printing or design. There will then be practically no exposure of the strip to any light 120 from outside the apparatus. The knob 47 should then be depressed. This action completes the electric circuit (by bringing into contact the terminals 43 and 44) and lights the lamp 3, causing a strong light to be projected through the glass 7 and sensitized strip 8 to the design or printing, and reflected back upon the strip 8, on which said 125

design or printing will be photographed. The depression of the knob 47 will cause the raising of the dog 29 from one of the recesses 28, and thus release the spring 32, to permit it to rotate the reel 12, if not otherwise prevented. As long as any material pressure remains on any portion of the surface of the strip 8, the spring 32 will not rotate the reel 12. By slowly drawing the device 10 downward with the glass 7 over the printing or design in the direction of the arrow (Fig. 1), the strip 8 will be gradually drawn off the reel 9 between the glass 7 and surface of 15 53, and be exposed to the light and said surface photographed thereon, and immediately afterward drawn up and around the reel 12 by the action of the spring 32, which also draws upon said reel the opaque strip 11 to further protect the previously exposed 20 strip 8 from the light. As soon as the pressure on the knob 47 is released the circuit will be broken, the light of the lamp put out, the dog 29 will be forced into one of the recesses 28, and the spring 32 will be held, 25 and there will be no further winding of the reel 12. The previously exposed strip can be used if desired from which to print other photographs.

My invention is particularly adapted for 30 copying pictures, designs and printing upon plane surfaces.

It will be evident that my invention is not limited to the precise method above described and that the apparatus above described may be varied or changed in many respects without departing from the invention.

What I claim as new, and desire to secure by Letters Patent, is—

40 1. The improved method of photographing, consisting in inserting different portions of a sensitized strip successively between the object to be photographed and a source of light, and withdrawing said portions of the strip from the action of light.

45 2. The improved method of photographing, consisting in placing a sensitized strip between the object to be photographed and a source of light, causing different portions 50 of said strip and object to be successively subjected to and released from the action of the light, and drawing within a practically light tight casing the portion of the strip that had been exposed to the light.

55 3. The improved method of photographing, consisting in placing a sensitized strip between the object to be photographed and a source of light, causing successive portions 60 of said strip to pass between successive portions of the object to be photographed and the light, and drawing within a practically light tight casing the portion of the strip that had been exposed to the light.

4. An apparatus for photographing, comprising a device for holding a source of

light and having means through which the light may pass, a practically light tight casing for holding a sensitized strip, the apparatus being adapted to have said strip extending across said means and between the 70 source of light and the object to be photographed, and means for drawing said strip within the casing.

5. An apparatus for photographing, comprising a device for holding a source of 75 light and having means through which the light may pass, a practically light tight casing for holding a sensitized strip, the apparatus being adapted to have said strip extending across said means and between the 80 source of light and the object to be photographed, and means for drawing said strip from the light passage and within the casing.

6. An apparatus for photographing, comprising a light projecting device having 85 means through which the light is projected, a practically light tight casing for containing a sensitized strip, and the apparatus adapted to have said strip extending over 90 said means and between said device and the object to be photographed, and a device for drawing said strip from said means and within said casing.

7. An apparatus for photographing, comprising a light projecting device having 95 means through which the light is projected, a practically light tight receptacle for containing a sensitized strip and the apparatus adapted to have a portion of said strip extending over said means, and between said 100 device and the object to be photographed and a device for drawing said strip from said means and away from exposure to light.

8. An apparatus for photographing, comprising a light projecting device having 105 means through which the light is projected, a practically light tight casing for containing a sensitized strip and surrounding said device so that a passageway is formed between said casing and means for the strip, 110 and the strip adapted to extend over said means and between the light projecting device and the object to be photographed, all as and for the purposes set forth.

9. An apparatus for photographing, comprising a light projecting device having 115 means through which the light is projected, a practically light tight casing for containing a sensitized strip and surrounding said device so that passageways are formed between opposite sides of said means and casing for the strip, and the strip adapted to extend over said means and between the light projecting device and the object to be photographed, and a device in said casing 120 for drawing said strip from said means and within said casing.

10. An apparatus for photographing, comprising a lamp casing which is practically light tight except a small area through 125

- which the light may be projected, a practically light tight casing for containing a sensitized strip and surrounding the lamp casing so that a passageway is formed between 5 said casing and area for the strip, and the strip adapted to extend over said area and between the lamp casing and the object to be photographed, all as and for the purposes set forth.
10. 11. An apparatus for photographing, comprising a lamp casing which is practically light tight except a small area through which the light may be projected, a practically light tight casing for containing a sensitized strip and surrounding the lamp casing so that passageways are formed between opposite sides of said area and the casing for the strip, and means in said casing for drawing said strip from said area and within said 15 casing.
12. An apparatus for photographing, comprising a lamp casing which is practically light tight except a small area through which the light may be projected, and said 20 casing formed to deflect the light through said area, a practically light tight casing for containing a sensitized strip and surrounding the lamp casing so that passageways are formed between opposite sides of said area and the casing for the strip, and means in said casing for drawing said strip from said 25 area and within said casing.
13. An apparatus for photographing, comprising a lamp casing, which is practically light tight except a small area, a translucent plate filling said area, and through 30 which the light may be projected, a practically light tight casing for containing a sensitized strip and surrounding the lamp casing so that a passageway is formed between said casing and plate for the strip, whereby said strip may be drawn outside of said apparatus and across said plate.
14. An apparatus for photographing, comprising a lamp casing, which is practically light tight except a small area, a translucent plate filling said area, and through 35 which the light may be projected, a practically light tight casing for containing a sensitized strip and surrounding the lamp casing so that passageways are formed between opposite sides of said plate and the casing for the strip, and means in said casing for drawing said strip from said plate and within said casing.
15. An apparatus for photographing, comprising a light projecting device having means through which the light is projected, a practically light tight casing for containing 40 a sensitized strip and inclosing said device so that passageways are formed between opposite sides of said opening and the casing for the strip, means in said casing for drawing said strip across said means and within said casing, and a light tight parti- 45
- tion in said casing separating the delivery portion of said strip from the part that is to be drawn back into the casing.
16. An apparatus for photographing, comprising a lamp casing, which is practically light tight except a small area through which the light may be projected, and said casing formed to deflect the light through said area, a practically light tight casing for containing a sensitized strip and 50 surrounding the lamp casing so that passageways are formed between opposite sides of said area and the casing for the strip, means in said casing for drawing said strip across said area and within said casing, and a light tight partition in said casing separating the delivery portion of said strip from the part that is to be drawn back into the casing.
17. An apparatus for photographing, comprising a lamp casing which is practically light tight except a small area through which the light may be projected, a practically light tight casing surrounding the lamp casing, a reel for a sensitized strip 55 inclosed in said surrounding casing, a spring take up reel also inclosed within said casing, means for holding the tension of said spring, and means for releasing said holding means, whereby the spring may rotate said reel and cause it to wind up said strip within the casing after it has been extended across the light area outside of the casing.
18. An apparatus for photographing, comprising a lamp casing which is practically light tight except a small area through which the light may be projected, a practically light tight casing surrounding the lamp casing, a reel for a sensitized strip 60 inclosed in said surrounding casing, a spring take up reel also inclosed within said casing, means for holding the tension of said spring, and movable means in a position to be controlled by the operator for releasing said holding means, whereby the spring may rotate said reel and cause it to wind up said strip within the casing after it has been extended across the light area outside of the casing.
19. An apparatus for photographing, comprising a lamp casing which is practically light tight except a small area through which the light may be projected, an electric lamp inclosed therein, a practically light tight casing surrounding the lamp casing, a reel for a sensitized strip 65 inclosed in said surrounding casing, a spring take up reel also inclosed within said casing, means for holding the tension of said spring, a circuit breaker adapted to be electrically connected with said lamp, and means connecting said circuit breaker with the spring holding means, whereby the action of completing the circuit to light the lamp will release said holding means, so 70

- that the take up reel can wind up said strip.
20. An apparatus for photographing, comprising a lamp casing which is practically light tight except a small area through which the light may be projected, an electric lamp inclosed therein, a practically light tight casing surrounding the lamp casing, a reel for a sensitized strip inclosed in said surrounding casing, a spring take up reel also inclosed within said casing, means for holding the tension of said spring, a normally broken circuit breaker adapted to be electrically connected with said lamp, and means connecting said circuit breaker with the spring holding means, whereby the action of completing the circuit to light the lamp will release said holding means, so that the take up reel can wind up said strip.
20. An apparatus for photographing, comprising a lamp casing which is practically light tight except a small area through which the light may be projected, an electric lamp inclosed therein, a practically light tight casing surrounding the lamp casing, a reel for a sensitized strip inclosed in said surrounding casing, a spring take up reel also inclosed within said casing, means for holding the tension of said spring, a circuit breaker adapted to be electrically connected with said lamp, a tension spring for keeping the circuit normally broken, and means connecting said circuit breaker with the spring holding means, whereby the action of completing the circuit to light the lamp will release said holding means, so that the take up reel can wind up said strip.
22. An apparatus for photographing surfaces, comprising a lamp casing which is practically light tight except a small area through which the light may be projected, a practically light tight casing surrounding the lamp casing, a reel for a sensitized strip inclosed in said surrounding casing, a spring take up reel also inclosed within said casing, means for holding the tension of said spring, manually operated means for releasing the tension of said spring, whereby the same may rotate said reel, and cause it to wind up said strip after it has been extended across said light area, and the entire apparatus adapted to be moved over the surface to be photographed with the exposed portion of the sensitized strip in contact with said surface.
23. An apparatus for photographing surfaces, comprising a lamp casing which is practically light tight except a small area through which the light may be projected, a practically light tight casing surrounding the lamp casing, a reel for a sensitized strip inclosed in said surrounding casing, a spring take up reel also inclosed within said casing, spring operating means for holding the tension of the spring of the take up reel,

manually operated means for releasing said holding means whereby the take up reel will be caused to rotate and wind up said strip after it has been extended across said light area, and the entire apparatus adapted to be moved over the surface to be photographed with the exposed portion of the sensitized strip in contact with said surface.

24. An apparatus for photographing surfaces, comprising a lamp casing which is practically light tight except a small area through which the light may be projected, a practically light tight casing surrounding the lamp casing, a reel for a sensitized strip inclosed in said surrounding casing, a spring take up reel also inclosed within said casing, spring operating means for holding the tension of the spring of the take up reel, means adapted to be manually operated to release said holding means, whereby the take up reel will be caused to rotate and wind up said strip, and after it has been extended across said light area, a tension spring normally acting to prevent said means from operating, and the entire apparatus adapted to be moved over the surface to be photographed with the exposed portion of the sensitized strip in contact with said surface.

25. An apparatus for photographing surfaces, comprising a lamp casing which is practically light tight except a small area through which the light may be projected, a translucent plate filling said area, a practically light tight casing surrounding the lamp casing, a reel for a sensitized strip inclosed in said surrounding casing, a spring take up reel also inclosed within said casing, means for holding the tension of said spring, manually operated means for releasing said holding means, whereby the spring may rotate said reel, and cause it to wind up said strip after it has been extended across said plate, and the entire apparatus adapted to be moved over the surface to be photographed with the exposed portion of the sensitized strip in contact with said surface.

26. An apparatus for photographing surfaces, comprising a lamp casing which is practically light tight except a small area through which the light may be projected, an electric lamp inclosed therein, a practically light tight casing surrounding the lamp casing, a reel for a sensitized strip inclosed in said surrounding casing, a spring take up reel also inclosed within said casing, means for holding the tension of said spring, a circuit breaker adapted to be electrically connected with said lamp, and manually operated means connecting said circuit breaker with the spring holding means, whereby the action of said manually operating means to complete the circuit to light the lamp, will release said holding means so that the take up reel can wind up

- said strip, and the entire apparatus adapted to be moved over the surface to be photographed with the exposed portion of the sensitized strip in contact with said surface.
- 5 27. An apparatus for photographing, comprising a lamp casing which is practically light tight except a small area through which the light may be projected, an electric lamp inclosed therein, a practically
- 10 light tight casing surrounding the lamp casing, a reel for a sensitized strip inclosed in said surrounding casing, a spring take up reel also inclosed within said casing, means for holding the tension of said spring, a circuit breaker adapted to be electrically connected with said lamp, and means connecting said circuit breaker with the spring holding means, whereby the action of said circuit breaker will release said holding means, so that the take up reel can wind up 20 said strip.

In testimony whereof, I have signed my name to this specification, in the presence of two subscribing witnesses.
